UNITED STATES PATENT OFFICE.

WALTER STANLEY BAKER, OF CONCORD, NEW HAMPSHIRE.

CLOTH-CLEANSING DEVICE.

No. 836,293.

Specification of Letters Patent.

Patented Nov. 20, 1906.

Application filed June 13, 1903. Serial No. 321,462.

To all whom it may concern:

Be it known that I, WALTER STANLEY BAKER, residing at Concord, in the county of Merrimack and State of New Hampshire, have invented certain Improvements in Cloth-Cleansing Devices, of which the following is a specification.

This invention relates to an article of manufacture for cleaning fabrics, and has especial reference to a brush for cleaning clothing, combined with a reservoir or receptacle for holding the cleaning agent, preferably in a liquid form, arranged so as to be fed down to the brush while the latter is being used, all of which I will proceed to describe and claim, reference being had to the accompanying drawings, which illustrate the invention, in which—

Figure 1 is a side elevation of the improved cleaning device. Fig. 2 is a section on line $x-x$ of the previous figure. Figs. 3 and 4 are respectively a top and side view of a follower detached from the holding-case. Fig. 5 is a side elevation of the brush portion detached from the holding-case, and Fig. 6 is a section on line $y-y$ of Fig. 5.

In the drawings, A represents the device as a whole; and it consists of a tubular case a , preferably of metal, upon the upper part of which is screwed a cap-piece c , a screw-thread being formed on the end of the case to engage the screw upon the cap. I provide a ring e of some compressible material, such as rubber, to rest upon the rib d , upon which the edge of the cap impinges to make a watertight joint.

The case a is divided into two chambers k and m by the partition b , which I term a "follower." The upper or disk part f projects slightly beyond the flange o and enters the circular depression h in the case, and its upper surface is perforated by numerous holes g . The upper chamber k serves as a receptacle or reservoir for a piece of cleaning-soap or for a liquid cleansing agent.

The brush portion j fills the lower chamber m quite tightly, and it is made from a strip of hair-cloth or other suitable material having horse-hairs or other stiff bristle-like flexible elements held loosely together by a warp of cotton or linen closely wound into a roll and then covered with a piece of cloth, preferably woolen, its edges overlapping and sewed to each other, leaving the ends open with the

hairs or bristles projecting, as at p . A circular piece of cloth i is placed under the disk f and serves as an obstruction or dam to prevent the liquid agent in the chamber k from passing down into the brush j too freely. In case the end of the brush should wear the follower b may be pressed downward until the rim f reaches and enters the second ring depression h^2 .

When the case is charged with liquid cleansing agent, if the case is held upside down, as it should be when not in use, none of the liquid will reach the brush, and when the device is to be used it is turned right side up and shaken, which causes the liquid to pass through the holes g in the disk into and to saturate the brush, and eventually it will trickle out at its open end, and when the brush is applied to the clothing to be cleansed the to-and-fro motion given to the device causes more of the liquid to descend until the cleansing operation is finished.

I claim as my invention—

1. As an article of manufacture, a cleansing device consisting of a tubular case with a cap on one end a movable partition dividing the case into two chambers, a brush closely fitting into the lower chamber composed of stiff bristle-like material surrounded by a band or support.

2. As an article of manufacture, a cleansing device consisting of a tubular case with a water-tight cap on one end, a perforated movable partition dividing the case into two chambers, a brush closely fitting into the lower chamber composed of stiff bristle-like material held together by a flexible band.

3. A cleansing device, consisting of a metal case, a water-tight cap screwed upon one end of the case, a perforated movable partition dividing the case into two chambers one of which is adapted to hold a fluid cleansing agent, a pad under the partition adapted to allow the said fluid agent to percolate therethrough slowly, and a brush in the second chamber composed of a roll of hair-cloth held together by a flexible band.

4. A cleansing device, consisting of a metal case, a water-tight cap screwed upon one end of the case, a perforated movable partition within the case having a projecting cap engaging a score inside the case, dividing the case into two chambers one of which is adapted to hold a fluid cleansing agent, a pad under

the partition adapted to allow the said fluid agent to percolate therethrough slowly, and a brush in the second chamber composed of a roll of hair-cloth held together by a flexible band.

5 In testimony whereof I have signed my name to this specification, in the presence of

two subscribing witnesses, this 8th day of June, 1906.

WALTER STANLEY BAKER.
